Inventor.

Joseph B. Tillinghast.

UNITED STATES PATENT OFFICE.

JOSEPH B. TILLINGHAST, OF RACINE, OHIO.

IMPROVEMENT IN PORTABLE FENCES.

Specification forming part of Letters Patent No. **38,131**, dated April 7, 1863.

To all whom it may concern:

Be it known that I, JOSEPH B. TILLINGHAST, of Racine, county of Meigs, and State of Ohio, have invented new and useful Improvements in Portable Board Fences; and I do hereby declare that the following is a full and exact description thereof, reference being had to the accompanying drawings, and to the letters of reference marked thereon, making a part of this specification.

The nature of my invention consists in fastening three rails J on the one side of four posts E, F, G, and H and two other rails, J, intermediately between the other rails, but fastened on the same side to three of the posts, E, F, and G, with extended ends, so as to be inserted in the spaces K K of the opposite end of the next panel, and interlocking with the posts E, G, and H of the next panel, to form a firm angular or worm fence.

To enable others skilled in the art to make and use my invention, I will proceed to describe its construction, as follows:

I use for convenience a platform of the height, width, and length of the panel to be made, upon which strips or guides D are permanently fastened, and between which posts E, F, G, and H are inserted, and rails J are nailed and fastened to the posts for the purpose of forming and making a light and portable board fence, that each panel will lock into the other and be made to suit the level or rising and falling ground.

A represents the platform upon which strips or guides D are permanently fastened with screws or nails, the guides being strips of board one inch in thickness and three or four inches apart, so that the posts E, F, G, and H may be laid or inverted between them. The posts are from three to four inches in thickness.

E represents the end post, which acts as a catch or lock against the post H of the next panel.

G represents a post which is intended to support the rails J and answer the purpose of a lever-bar.

F represents the center post to support the rails J.

All the posts extend three or four inches below the bottom rail, so as to rest on stone or plank.

Having inserted the posts E, F, G, and H between the strips D, I place five boards or rails J upon them, straight and level for level ground, or at an incline, so as to suit rolling or uneven ground. The top rail J is then fastened by nails or screws to the four posts E, F, G, and H. The second rail is fastened by nails or screws to the three posts E, F, and G, the end of rail projecting two or more feet beyond the post E. The third rail J is fastened like the first. The fourth rail is fastened and projects like the second, and the fifth or lower rail J is fastened to correspond with the first or top rail. Two panels being thus finished, the ends of the second and fourth extension rails J are then inserted in the spaces K of the next panel, and the panels are interlocked by the ends of rails J pressing against the post G and the post E resting against the post H, forming an angular or worm fence, having an equal pressure on all sides and not liable to get out of place, or be so easily affected or injured by storms, and having a decided advantage in being quickly and regularly constructed and put up.

What I claim as my invention, and desire to secure by Letters Patent, is—

The panels having the posts all one side, provided with the extension-rails L, fitting into the spaces K, with the post E, interlocking with the post H, all constructed in the manner and for the purpose set forth.

JOSEPH B. TILLINGHAST.
